WASHING MACHINE

Herbert L. Johnston, Troy, Ohio, assignor to The Hobart Manufacturing Company, Troy, Ohio, a corporation of Ohio

Original application August 30, 1930, Serial No. 478,978. Divided and this application January 11, 1933, Serial No. 651,181. In Canada August 25, 1931

19 Claims. (Cl. 141—9)

This invention relates to washing machines.

One of the principal objects of the invention is the provision of a washing machine of simple construction which is adaptable to various installation conditions, may be readily set up for service, and is capable of sustained use without deterioration of the washer parts.

Another object of the invention is the provision of a washing machine which is so constructed that the various operations may be carried out in rapid sequence, the arrangement of parts being such that the operator is required to follow a proper procedure in the cycle of operations.

Another object of the invention is the provision of a washing machine having a movable door or doors which are positively interlocked with the control members for the wash water and rinse water supplies so as to prevent opening of the door or doors when either of the control members is turned on, and to prevent turning on of either of the control members when a door is moved out of closed position.

Still another object of the invention is the provision in a washing machine of this character having a sliding door or doors of an improved form of counterweight construction for the door or doors, affording ready assembly of the counterweight.

Other objects and advantages of the invention will be apparent from the following description, the accompanying drawings and the appended claims.

This is a division of my copending application Serial No. 478,978, filed August 30, 1930.

In the drawings, in which like characters of reference designate like parts throughout the several views thereof—

Fig. 1 is a side elevational view of a washing machine constructed in accordance with this invention; some of the parts being shown in section for clearness of illustration;

Fig. 2 is an end elevation of the washing machine;

Fig. 3 is a plan view of the washing machine in which some of the parts are broken away;

Fig. 4 is an enlarged detail of a portion of the valve control;

Fig. 5 is a fragmentary showing of the valve control;

Fig. 6 is a fragmentary plan view of a portion of the valve control for the wash liquid supply; and

Fig. 7 is a detail sectional view taken on the plane of the line 7—7 of Fig. 5.

The washing machine comprises generally a

frame within which is mounted a wash water circulating pump and driving motor therefor, a washing compartment, and an enclosing housing for the washing compartment; the housing being provided with suitable doors for the reception and withdrawal of racks of dishes and like articles.

Referring to the drawings, which disclose a preferred embodiment of the invention, the machine is provided with a cast metal base 10 having a bottom portion 11 and extending flanges 10 12; the base being substantially rectangular in shape. Suitable supporting members 13, which are preferably of angular cross section, extend upwardly from the corners of the base portion 10 for the support of the washing machine structure. 15 The washing compartment comprises an open top tank which is composed of side walls 14 and a bottom wall 15 suitably joined as by welding to form a liquid tight compartment which may be attached as a unit to the upright members 13 to which it is secured as by means of bolts. The bottom wall 15 comprises an upper substantially horizontally extending portion 16 which extends part way across the bottom of the tank, then extends downwardly as indicated at 17 to substantially the level of the base 10, then continues on a substantially horizontal plane to join the rear wall of the tank. This arrangement of parts provides a washing compartment, 20 comprising the four vertically extending walls 14 and the bottom wall 15, which in its lower extended portion incorporates a water supply chamber or sump 18 formed by the downwardly extending wall portion 17 and the side walls 14. The area beneath the bottom wall portion 16 and adjacent the wall portion 17 provides a space 25 which is freely open and exposed at the sides and front of the machine. This space provides a readily accessible location for a wash water circulating pump 20 and its driving motor 21; the driving motor being suitably supported upon the base portion 11 as by means of attaching bolts 22.

The rear wall of the tank has attached to it a wall portion 14' which extends upwardly to the top of the machine and forms part of an 45 enclosing casing for the washing compartment. The side and front walls 14 terminate in outwardly extending flanges 25 which are shown positioned at substantially the level of a work table or shelf to permit racks of dishes to be 50 readily moved into and withdrawn from the machine. Angle bars 26, which are positioned at the forward corners of the washing compartment and are suitably joined to the members 13 by connecting bolts, extend upwardly from the 55

level of the flanges 25 and, with the rear wall 14', provide a support for the top 28 of the machine. The angle bars 26, in cooperation with the rear wall 14', form guides for suitable movable doors 30 which in their closed position extend from the flanges 25 to the top of the machine and, with the rear wall 14', provide a water tight enclosing housing for the washing compartment.

10 The supporting frame comprising the angle members 13 and 26 is provided with brackets 32 for the support of suitable rack guides or tracks 34 which are adapted to carry the racks or trays holding the dishes or articles to be washed within the casing. The rack guides 34 may be shaped to permit the dish carrying racks to be entered at one side of the machine and be withdrawn from the opposite side, or to be entered from one side and withdrawn from 20 either of the adjacent sides; this arrangement of parts providing a machine which is readily adaptable to meet various conditions of installation. The doors are adapted to slide vertically and operate in grooves 36 formed between the 25 angle members 26 and guide members 37 which are attached to the inside surface of the angle members.

A mechanism is provided whereby the two doors through which the racks are entered or 30 withdrawn may be operated simultaneously; the arrangement being such that movement of one door automatically effects corresponding movement in the other door. This door operating mechanism includes a counterbalance weight so 35 that the door movement may be accomplished with but little effort. Each of the doors regularly used, which as illustrated in Fig. 3 comprises the oppositely positioned doors, is provided with a connecting chain 38 which is attached 40 at one end to the lower edge of the door by means of an attaching bracket 39 and is connected at the opposite end to the counterbalancing weight 41; suitable supporting pulleys 42 being provided for the guidance of the chains 45 38. The counterbalance 41, which is preferably a cast member, is provided with oppositely extending forks 44 which are adapted to engage spaced rods 45 to properly guide the travel of the weight 41. The guide members 45 are supported 50 from the machine by suitable brackets 46 and are shaped to stand substantially parallel throughout the normal range of travel of the counterweight, and to flare outwardly beyond the normal range of travel so that by lifting the 55 weight to a position beyond its normal range of travel it may be readily withdrawn from the guides. This arrangement of guide members facilitates the assembly of the machine and permits the counterweight to be inserted in operating position without disturbing the assembled guide members. The weight of the member 41 is adjusted to substantially balance the combined weights of the two doors to which it is connected so that upon manual actuation of 60 one door the balance of weight will be such as to automatically actuate the other connected door. The chains 38 pass through the top cover member 28 within suitable guides 48 and, as mentioned, are attached to the lower edges of the 65 doors so that these doors may be raised to substantially the full opening of the housing to completely expose the interior of the housing. The upward movement of the doors is limited by contact of the attaching members 39 with rubber bumpers 50 which are carried upon brackets 70

51 suitably mounted on the supporting angles 26. Downward movement of the counterweight 41 is limited by springs 53 which are positioned upon the guides 45 and rest upon the lower supporting brackets 46. The arrangement of counterweight and connecting chains is such that any two doors may be readily attached to the counterweight; the attached doors being those in the path of travel of the dish racks.

The electric motor 21 which drives the pump 10 20 is provided with an extending armature shaft 60 which extends through a suitable stuffing box 61 into the interior of the pump for actuation of the pump impeller 62. The housing 64 of the pump is provided with an attaching 15 structure 65 whereby the pump is supported at one side directly from the frame of the motor 21. The pump housing, which is preferably of substantially cylindrical cross section, encloses the impeller 62 which comprises a plate portion 67 upon which are formed a plurality of vanes 68. Upon actuation of the pump by its driving motor wash water is drawn from the sump through an intake 70 connecting the sump to a suction opening in the pump housing 64. 25 The rotating impeller forces the water drawn from the sump through a discharge pipe 71, preferably formed as an integral part of the housing 64, to a valve 72. The motor and pump, including the circulating pipes 70 and 30 71 comprise a unitary structure which may be readily assembled in position upon the washing machine by merely attaching the motor to the base 10 by means of screws 22, by completing the connection of the pipe 71 to the valve 72, 35 and by providing a water tight joint at the point of entrance of the suction pipe 70 within the sump 18. As shown, the end of the pipe 70 which enters the sump 18 through an opening 18' is threaded for the reception of suitable lock nuts 70'; one being provided on the pipe on the exterior of the sump while the other is adapted to be positioned on the pipe on the interior of the sump after assembly. Suitable gaskets are provided between the nuts and the 45 sump wall so that upon drawing the nuts tight a water tight joint will be provided. The valve 72 is shown positioned on the interior of the washing compartment adjacent the horizontally extending wall 16 and is provided with a contacting flange 73 which is adapted to coact with a similarly shaped flange 74 on the discharge pipe 71 to provide a water tight passage for washing fluid from the pump through the casing member 16 to the interior of the valve 55 72.

The valve 72 comprises a casing 75 which is substantially cylindrical in cross section and which is provided with suitable passages 76 and flanged connections 77 for the attachment of connecting 60 pipes leading to suitable wash water discharge nozzles such as the rotary wash arms shown. A hollow cylindrical valve member 78 is rotatably mounted within the valve casing 75 and is provided with opposed slots 79 which in open position 65 of the valve member are adapted to coincide with discharge openings 76 in the valve casing connecting to the wash arm conduits. The provision of separate slots 79 in the valve member for each wash arm conduit results in an independent connection between the wash water supply pipe 71 and each conduit so that the flow of water to each wash arm is balanced. The valve member 78, which is rotatably mounted within the casing 75, is provided with an axially extending stem 80 70 75

which is suitably supported within a sleeve 81 formed in the valve housing. The stem 80 extends beyond the exterior of the housing 75 and has fixed to it an operating arm 82 to which suitable linkage is attached connecting the arm 82 to an operating handle. As shown, the operating handle comprises a lever 85 which is positioned on the exterior of the machine adjacent a corner of the top 28. The lever 85 is fixed to a rotatably movable connecting rod 86 which is suitably supported at one end by means of a bracket 87 provided on the top member 28 and is guided at its lower end in a bracket 88 which is shown formed on a portion of the wash water distributing structure. The rod 86 has attached to it a crank arm 89 which has pivotally connected to it at 90 an adjustable linkage 91 whose opposite end is pivotally connected at 92 to the arm 82. Movement of the control arm or operating handle 85 results in corresponding movement of the valve member 78.

Wash water from the valve 72 is carried to the several wash arms by means of the conduits or connecting pipes which are attached by suitable means to the flanges 71 of the valve casing 75; the pipe 95 providing a communicating passage from the valve to a lower wash arm 96, while the pipe 97 provides a fluid passage to an upper wash arm 98. As shown, the pipe 95 extends from the valve 72 to substantially the vertical center line of the machine and there is provided with an elbow 100 which terminates in an open upstanding end. A vertical shaft 101 is suitably supported within the elbow 100 and forms a journal upon which the wash arm 96 is mounted. This wash arm 96 comprises a hollow member which is freely rotatable upon the supporting shaft 101 and is provided with a plurality of spray openings 103 which direct the wash water upwardly. Certain of the spray openings are inclined so that the reaction forces of the water on the nozzles impart a rotating movement to the wash arm. The wash arm is maintained in position upon the shaft by means of a hand nut 104 which is threadedly received upon the upper threaded end of shaft 101.

The distributing pipe 97, which is positioned within the confines of the washing compartment and housing, extends from the valve casing 75 to a corner of the washing machine housing, then extends upwardly toward the top of the housing, then inwardly for attachment to an elbow or conduit member 105 which is positioned within and substantially upon the vertical center line of the machine. The member 105 provides a fluid conduit for wash water from the pipe 97 to the upper wash arm 98, which is rotatably supported by a stem or shaft (not shown) which is mounted in a bearing carried by a supporting member 108 mounted on the exterior of the cover 28.

Means are provided for supplying rinse water to the interior of the housing including a supply pipe 157, which may be attached to some suitable source of rinsing water, and a control valve 158 which is adapted to be actuated from the control lever 85. A pipe connection 160 extends from the valve 158 to the interior of the housing where branch pipes 160' connect to suitable rinse nozzles 161 which are shown positioned adjacent the top of the washing compartment to direct sprays of rinse water downwardly towards the articles being washed. A pipe 162, which is shown positioned adjacent the rear wall of the housing and out of the path of travel of the dish racks, extends downwardly from the pipe 160 and has connected to it branch pipes 162' to which additional rinse

nozzles 163 are attached; the nozzles 163 being directed upwardly. The valve 158 is provided with a spring pressed control stem 164 which is adapted to constantly urge the valve to closed position. An arm 165 is pivotally supported at 166 upon a bracket 167 carried by the valve 158; the arm 165 being provided with an adjustable stud 168 which is adapted upon actuation of the arm to contact with the stem 164 to open the valve. The arm 165 is positioned so that upon movement of the lever 85 in one direction a roller member 170 carried by the lever 85 will contact with and actuate the arm 165 to open the rinse valve.

The rinse valve actuating arm 165 and the wash water valve member 78 are positioned with respect to one another so that actuation of the control lever 85 in one direction will permit opening of one valve and movement in the reverse direction will permit opening of the other valve. As shown, the lever 85 will, upon being moved in a counterclockwise direction from the neutral position shown in Fig. 4, contact with the arm 165 to actuate the rinse valve. Upon movement of the valve in a clockwise direction from neutral position, the valve member 78 will be moved to bring the slots 79 into registration with the passages 76 to permit the flow of wash water from the pump to the wash arms 96 and 98. For the convenience of the operator the wash lever 85 carries a spring pressed detent 171 which cooperates with spaced holes 172 formed in the supporting bracket 87 to permit the control lever 85 to be maintained in either neutral or washing position without requiring the operator to hold the valve in either of these positions. As shown, a detent retaining hole 172 is provided at the neutral position, and a second hole 173 is provided to maintain the valve handle in washing position. No detent hole is provided for the rinse position as it is desirable to require the operator to intentionally maintain the valve in this position against the tension of the rinse valve spring to prevent the waste of rinse water. Upon completion of the washing operation, the operator moves the control lever 85 in a counterclockwise direction from washing position to rinsing position where the valve must be held to be maintained open against the spring tension exerted on the stem 164. At this time hot rinsing water is supplied to the rinsing nozzles and inasmuch as this operation usually lasts about four to six seconds the spring tensioned control is provided so that the control will not be accidentally left in rinsing position with consequent waste of rinse water.

To insure that the proper procedure in the cycle of operation will be followed by the operator the control lever 85 is provided with means which permits actuation of the control valves only when the doors are closed and prevents actuation of these valves when the doors are open. As shown, the lever 85 is provided with outwardly extending flanges 175 which have provided therein slots 176 so positioned that with the lever 85 in neutral position (shown in Fig. 4) the doors 30 adjacent the control lever 85 may be opened by sliding upwardly through the slots 176. In any other position of the control lever the flanges overlie the upper edges of these doors so that the operator is prevented from raising these doors during a washing or rinsing operation. This arrangement of interlock between the control lever and the doors, and the provision of the interconnected counterweight makes it impossible to move the control lever from neutral position when any of the doors are opened; the 75

doors positioned adjacent the interlock flange being adapted to cooperate with the flange directly to prevent valve movement, while the door positioned away from the flange is adapted to 5 cooperate through the interconnecting counterweight chains to actuate an adjacent door. With the valve in operating position the adjacent doors are locked closed by the interlock flange. The 10 remotely positioned door, although not positively maintained closed, is relieved of the balancing effect of the counterweight upon latching the adjacent doors. Consequently upon opening the 15 remotely positioned door under these circumstances it is necessary to lift the entire weight of the door. This serves as a reminder that the door is not to be opened.

The side of the wash water chamber or sump 18 is provided with an overflow connection 193 which is connected by a pipe 194 to a drain line 20 195. A drain pipe 197 connects the bottom of the chamber or sump 18 to a drain valve 198 having a suitable control handle 199 arranged within convenient reach of the operator so that the sump may be quickly drained into the drain pipe 195. 25 The overflow connection 193 is constantly maintained open to the drain pipe 195 so that a maximum predetermined fluid level in the sump will not be exceeded, and also to permit surface layer of grease and waste material to be drained 30 from the washing fluid. The drain connection 197 is under control of the handle 199 and is opened only upon actuation of the handle.

For convenience in placing the machine in operation and to permit a rapid filling of the chamber or sump 18 with wash water at the beginning 35 of washing operations a pipe connection is provided to the washing compartment from a supply of wash water and is under control of the hand valve 200. The pipe connecting to the hand 40 valve 200 may be joined to the pipe 157 supplying water to the rinse valve. To raise the temperature of the wash water within the sump a steam line may be provided for connection into the sump; a hand valve 202 being provided in 45 this steam connection to regulate the flow to the interior of the sump where any suitable form of injector or bubbler arrangement may be provided to effect transfer of heat from the steam to the wash water.

50 It will now be apparent that there is provided a washing machine of compact form and simple construction which is adapted to meet various conditions of installation requirements and which is adapted for rapid operation. The few moving 55 parts of the machine are so constructed and protected against deterioration and wear that the machine may be operated for long periods of time without the need for replacement of parts. The control mechanism for the machine is so 60 arranged that the operator is required to follow a proper procedure in the cycle of operation and is thereby protected against injury to himself by scalding or injury to the mechanism of the machine.

65 While the forms of apparatus herein described constitute preferred embodiments of the invention, it is to be understood that the invention is not limited to these precise forms of apparatus, and that changes may be made therein without 70 departing from the scope of the invention which is defined in the appended claims.

What is claimed is:

1. In a washing machine, a casing, a sliding door in said casing having parallel side edges, 75 spaced guide members in the casing extending

lengthwise of the door and engaging the door side edges for guiding movement thereof, fluid distributing means, a valve in said fluid distributing means, valve operating means, and an interlock member having connection with said valve 5 operating means and movable therewith, said door and interlock member having intercepting paths of travel, the interlock member moving into the path of the door upon opening movement of the valve by the operating means to prevent opening movement of the door by overlying one guided edge of the closed door adjacent the door end, and said door, upon opening, moving into the path of the interlock to prevent opening of the valve 10 when the door is open. 15

2. In a washing machine, a casing, a sliding door in said casing, fluid distributing means, a valve in said fluid distributing means, valve operating means, said valve operating means incorporating a notched flange movable therewith in the path of said door and adapted to cooperate directly with the door to provide an interlock, said flange notch being positioned with respect to the door to prevent actuation of the valve when the door is in an open position. 20

3. In a washing machine, a casing, a plurality of doors in said casing, a counterweight for said doors, means connecting a plurality of said doors to said counterweight whereby said counterweight is effective to urge each connected door toward 30 open position, fluid distributing means in said casing, means for controlling the supply of fluid to said distributing means, and means effective as an interlock between one of said doors and the said control means to prevent movement of 35 the said one door from closed position when fluid is being supplied to said distributing means, the means connecting each of said doors to the said counterweight being so constructed that when the interlock is thus operated to prevent opening of 40 the said one door the counterweight is rendered ineffective with respect to opening movement of the other door.

4. In a washing machine, a casing, a plurality of doors in said casing, at least one of said doors being operably remote from the remaining doors, counterweight mechanism including a plurality of connecting means attached to a selected plurality of said doors to make the counterweight mechanism effective in operation upon the selected ones of the plurality of doors, means within said casing for effecting distribution of fluid therein, means for controlling the supply of fluid to said distributing means, and means effective as an interlock between the said fluid control 50 means and a door operatively connected to said counterweight mechanism, said interlock means being effective to positively prevent movement of an associated door from closed position when the fluid control means is open, and effective 55 through the counterweight mechanism in restraining opening movement of another door connected to the counterweight mechanism.

5. In a washing machine, a casing, a plurality of spaced individually operable doors in said 65 casing, fluid distributing means, a valve in said fluid distributing means, valve operating means, and means cooperating with said plurality of doors to prevent actuation of the valve when any one of the doors is open and prevent actuation of said doors when the valve is open. 70

6. In a washing machine, a casing, a vertically movable sliding door in said casing, fluid distributing means, a valve therefor, valve operating means, a control handle attached to said valve 75

- operating means, a latching member having connection with said control handle, said door moving into the path of said latching member to interlock with said latching member when the door is opened to prevent actuation of the control handle and thus permitting actuation of the control handle only when the door is closed.

5. In a washing machine, a casing, a door in said casing, wash water distributing means, rinse water distributing means, a control valve in each of said distributing means, operating mechanism for each of said control valves, a single control handle cooperating with said operating mechanisms and adapted to provide alternate actuation 10 of said valves, and interlock mechanism effective to prevent actuation of either of said valves when the door is open and actuation of the door when either of said valves is open.

6. In a washing machine, a tank, a wash liquid distributor, a rinse liquid distributor, a movable closure for said tank confining the fluids from said distributors, means for controlling the supply of wash liquid distributor to said wash liquid distributor, means for controlling the supply of 15 rinse liquid to said rinse liquid distributor, a single manual control member for both of said controlling means for the wash liquid and rinse liquid, and interlock mechanism positively effective directly between said movable closure and said manual control member for preventing actuation 20 of said control member to supply either wash liquid or rinse liquid when the movable closure is in open position, and preventing movement of said closure out of closed position when said control member is in position to supply either wash liquid or rinse liquid to their respective distributors.

7. In a washing machine, a tank, liquid distributing means, means for supplying wash liquid 25 to said liquid distributing means, means for supplying rinse liquid to said liquid distributing means, a movable closure for said tank confining the liquids from said distributing means, a single control member for controlling both the wash liquid supply means and the rinse liquid supply means, and interlock mechanism positively effective directly between said movable closure and said control member for preventing actuation of 30 said control member to supply either wash liquid or rinse liquid when the movable closure is moved out of closed position, and preventing movement of said closure out of closed position when said control member is in position to supply either wash liquid or rinse liquid.

8. In a washing machine, a tank having a rack receiving opening, a fluid distributor, means for supplying fluid to said distributor, a door 35 slidably in a plane for closing said rack receiving opening to confine fluid from said distributor within said tank, a control member for actuating said fluid supplying means, said control member having a portion for direct engagement with the door and located in the path of the opening movement of said door when in fluid supplying position to overlie and positively prevent opening of said door, said door in open position having a portion in the path of movement of said control member to positively prevent actuation of said control member to supply fluid.

9. In a washing machine, a tank having a rack receiving opening, a fluid distributor, means for supplying fluid to said distributor, a slidable door for closing said rack receiving opening to confine fluid from said distributor within said tank, a control member for actuating said fluid supplying 40 means, and an interlock member fixed to said control member and positively moved thereby, said interlock member being moved into a position in advance of the path of sliding movement of said door when the control member is moved to supply fluid to said distributor to prevent opening of said door, said interlock member being moved out of the path of sliding movement of said door when the control member is moved to cut off the supply of fluid to said distributor, and said door being moved when opened into the path of movement of said control member and interlock to prevent movement of the control member to supply fluid to said distributor.

10. In a washing machine, a tank having a rack receiving opening at one side thereof, a fluid distributor, means for supplying fluid to said distributor, a door upwardly slidably along said tank for uncovering said rack receiving opening and downwardly slidable to close said opening to confine fluid from said distributor, a control member for actuating said fluid supplying means, and an interlock member having connection with and movable with said control member and overlying the upper end of said slidable door in closed position thereof, said interlock member being moved by said control member to a position in the path of movement of said slidable door to prevent opening of said door when the control member is moved to position to supply fluid to said distributor, and being moved to a position out of the path of movement of said door when the control member is moved to cut off the supply of fluid to said distributor, said door being moved when opened into direct interlocking engagement with said interlock member to prevent movement of the control member to supply fluid to the distributor.

11. In a washing machine, a tank having a rack receiving opening, a wash liquid supply means, a rinse liquid supply means, a movable closure for closing said rack receiving opening and confining the wash liquid and rinse liquid from said supply means, a single control member for said wash liquid and rinse liquid supply means movable from a neutral position to a wash position and further movable to a rinse position, and an interlock member having connection with and positively movable with said control member into the path of movement of said closure to prevent opening of said closure when the control member is moved into either wash position or rinse position, said interlock member being moved out of the path of movement of said closure when the control member is moved to neutral position, and said closure being moved when opened into direct interlocking engagement with said interlock member to prevent movement of said control member to either wash position or rinse position.

12. In a washing machine, a tank having a rack receiving opening, a wash liquid supply means, a rinse liquid supply means, a slidable door for closing said rack receiving opening and confining the wash liquid and rinse liquid from said supply means, a single control member for said wash liquid and rinse liquid supply means including a control handle rotatable from a neutral position in one direction to a wash position, and rotatable from the neutral position in the opposite direction to a rinse position, and an interlock member having connection with and positively movable with said control member into the path of sliding movement of said door to prevent opening of said door when said control handle is rotated to either wash or rinse positions, said interlock member

having a slot which is aligned with said door when the control handle is in neutral position to provide for opening of the door, said door being moved when opened into said slot in interlocking engagement with the interlock member to prevent movement of said control handle to either wash or rinse positions.

15. In a washing machine, a casing, a fluid distributor, means for supplying fluid to said distributor, a plurality of individually operable spaced doors for said casing for confining the fluid from said distributor, a control member for said fluid supplying means, and interlock means having connection with and movable with the control member, said interlock means cooperating with said plurality of doors to prevent actuation of said control member to supply fluid to said distributor except when all said doors are closed, and to prevent opening of any one of said doors except when said control member is in position cutting off the supply of fluid to said distributor.

16. In a washing machine, a casing having a rack receiving opening and a separate rack discharge opening, a fluid distributor, means for supplying fluid to said distributor, separate doors for closing said openings to confine the fluid from said distributor, a control member for said fluid supplying means, and an interlock member having connection with and positively movable with said control member, said interlock member having portions movable into the direct path of movement of both of said doors to prevent opening thereof when said control member is actuated to supply fluid to said distributor, each of said doors being moved when opened into direct interlocking engagement with said interlock member to prevent movement of the control member to supply liquid to the distributor when either of said doors is open.

17. In a washing machine, a casing having at least three rack receiving and discharge openings, a fluid distributor, means for supplying fluid to said distributor, three separate doors for closing said openings for confining the fluid from said distributor, a counterweight, connections from two of said doors to said counterweight so

that said two doors operate in unison, a control member for said fluid supplying means, and interlocking means between said control member and one of said two counterweighted doors to prevent opening of said two doors under the action of said counterweight when said control member is in position to supply fluid to said distributor, said interlocking means being also effective between said control member and said third door to also prevent opening of the said third door in the fluid supplying position of said control member.

18. In a washing machine, a casing having a rack receiving opening and a rack discharging opening, a wash liquid supply means, a rinse liquid supply means, separate doors for closing said openings and confining the liquid from said supply means, a single control member for both said wash liquid supply means and said rinse liquid supply means, and movable from a neutral position to a wash position and further movable to a rinse position, and interlock means preventing opening of both of said doors when the said control member is in either wash position or rinse position, and preventing actuation of said control member to either wash position or rinse position when either one or both of said doors are open.

19. In a washing machine, a casing having three doors, a counterweight mechanism, means connecting a selected pair of the doors to the counterweight mechanism, means for effecting fluid distribution within the casing, means for controlling the supply of fluid to said distributing means, means for actuating the fluid control means comprising an interlock effective between the fluid control means and another pair of said doors, said interlock being effective to prevent movement of either of the associated doors from closed position when the fluid control means is actuated to supply fluid to said distributing means, and said counterweight mechanism being effective as an impositive interlock to control movement of the other door when the fluid control means is so actuated.

HERBERT L. JOHNSTON.
